UNITED STATES PATENT OFFICE.

BERNARD TOULOUSE AND JOHN DELORIEUX, OF SAN FRANCISCO,
CALIFORNIA.

WINE-PRESS.

SPECIFICATION forming part of Letters Patent No. 367,122, dated July 26, 1887.

Application filed August 26, 1886. Serial No. 211,943. (No model.)

To all whom it may concern:

Be it known that we, BERNARD TOULOUSE and JOHN DELORIEUX, citizens of the United States, residing at San Francisco, in the county 5 of San Francisco and State of California, have invented certain new and useful Improvements in Wine-Presses, of which the following is a specification, reference being had to the accompanying drawings, in two sheets.

Our invention relates to certain improvements in that class of wine-presses in which a vertical screw and nut are employed, together with a mortise-wheel and cotter keys or wedges; and our improvements consist in certain novel construction and arrangement of 15 collars and combination-levers, whereby a cumulative power is obtained and the pressure augmented.

The nature of these improvements and the 20 manner in which we proceed to construct, combine, and use the same to accomplish the desired end and object are fully set forth and explained in the following description, the said drawings being referred to by letters and 25 figures.

Figure 1 is a view in elevation of our wine-press. Fig. 2 is also a view in elevation, showing the combination-levers. Fig. 3 is a 30 plan of the same, showing the operating-lever turned outward the full stroke. Figs. 4, 5, 6, 7, and 8 are views in detail of different parts of the mechanism. Fig. 9 is an enlarged vertical section of the entire press.

Let A represent the vertical stationary screw 35 which passes through the follower-piece B. The vertical screw carries the two collars C and D, and between these two collars the threaded mortise-wheel E is operated by a system of combination-levers, to be hereinafter fully described.

The collar C is provided with a flange, C^x, 40 which in operation rests upon the top face of the follower-piece B. Upon opposite sides of the collar C are cast the posts or studs F F^x. The latter extending outwardly forms an arm, 45 to be also hereinafter fully described. The upper ends of these posts or studs have inwardly-projecting hooks or lugs F², to receive and retain the flange of the combined mortise- 50 wheel and threaded sleeve D^x, as shown in Fig. 2.

Within the upper end of the collar C are arranged the friction wheels or rollers G, upon which the lower face of the flange H of the combined mortise-wheel and threaded sleeve 55 moves. The mortise-wheel is constructed with the usual mortises, I, and from the periphery of the wheel extend the radial arms I^x for convenience in running the threaded sleeve and wheel up or down upon the vertical screw irrespective of the movement of the levers connected to the collars C and D. The lower end of the collar D rests upon the mortise-wheel and works around the threaded sleeve D^x, 60 which is formed integral with the mortise-wheel through the medium of the lever-arm cast upon one side of the collar having an elongated slot, J, formed thereon, within which works a crank-pin, J^x, passing through the slot and entering a hole in the jointed and 65 pivoted lever D² at the end of the crank-arm D² of the collar C, and thus the compound levers of the press are formed and combined. The crank J^x works in a frictional sleeve, K.

The collar D is provided with mortises L, 70 within which the wedges or cotter-keys M play up and down as the collars and threaded nut are operated. The lower portion of these wedges or keys are beveled, as shown, and enter the mortises of the mortisewheel or disk 80 in operation. It will thus be seen that the threaded sleeve, with its mortise wheel or disk, operates between the two movable collars C and D, while the lower end of the nut is kept in position upon the friction-rollers in the upper end of the collar C by the hooked lugs F².

In practice the threaded sleeve is first screwed down with the hands by means of the radial arms of mortise-disk until the lower collar, C, rests upon the follower-piece, in which position the combination-levers are operated backward and forward by the long lever-handle shown in Fig. 1, when the keys or wedges will rise and fall alternately within the slots of the collar D and mortises of the disk or mortise-wheel E, and turn the threaded sleeve downward on its vertical screw with as great speed as the movements of the operating-levers will impart, the two levers working in unison upon the frictional crank-pin, the latter traveling 95 in the elongated slot as the reciprocating movements of the levers are made.

Having thus described our invention, what we claim, and desire to secure by Letters Patent, is—

1. The combination of the vertical stationary threaded screw-shaft, the lower collar, C, having flange C^x, hooked posts F and F^x, crank-arm D², and the series of friction-rollers G, arranged in said collar, the collar D, provided with a slotted arm, the jointed and pivoted lever D³, crank-pin J^x, and the combined mortise-wheel and threaded sleeve, all constructed, arranged, and operating substantially as set forth.

2. The combination of the upper collar having an arm formed with an elongated slot, a

traveling crank-pin operating therein, the lower collar, C, having the rigid arm D², and the lever D³, pivotally connected to arm D² and connecting with said upper arm by means of the crank-pin, whereby a united operation 20 of the levers is secured, substantially as described.

In testimony that we claim the foregoing we have hereunto set our hands and seals.
